UNITED STATES PATENT OFFICE.

EMORY J. BENEDICT, OF DELL RAPIDS, DAKOTA TERRITORY.

TRUCK.

SPECIFICATION forming part of Letters Patent No. 366,554, dated July 12, 1887.

Application filed April 14, 1887. Serial No. 234,812. (No model.)

To all whom it may concern:

Be it known that I, EMORY J. BENEDICT, a citizen of the United States of America, residing at Dell Rapids, in the county of Minnehaha and Territory of Dakota, have invented certain new and useful Improvements in Trucks; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to certain new and useful improvements in hand-trucks, the object of my invention being to provide a simple, cheap, and effective hand-truck, which is so constructed that it may be used for handling 20 boxes, barrels, and bags with the same facility as trucks designed for each special purpose; and the same consists in the construction and combination of the parts, as will be herein-after fully set forth, and specifically pointed 25 out in the claims.

In the accompany drawings, which illustrate my invention, Figure 1 is a perspective view of a hand-truck constructed in accordance with my improvements. Fig. 2 is a longitudinal sectional view. Fig. 3 is a front view showing the bail or swinging nose thrown down in full lines and elevated in dotted lines. Fig. 4 is a detail perspective view of the handle. Fig. 5 is a longitudinal sectional view of 35 a modification.

A refers to the main or body portion of the truck, which is preferably made of a single piece of board of the requisite thickness and width. The sides of this board are cut away 40 or curved inwardly to form a central handle portion, the sides of which are parallel with each other, and to the terminal portion of which is secured a handle portion, B, which consists of side pieces, b, of malleable metal, 45 which are provided with inturned portions b', which have openings, through which screws pass for attaching the same to the handle. These side pieces, b b, are connected to each other by a cross-bar, which forms a suitable 50 hand grasping device.

To the under side of the wide end of the board A, which forms the body portion of the truck, is attached, by suitable bolts, a downwardly-projecting support or bearing for the shaft or axle, which extends across the end of the board A. This axle support or bearing may be struck up of a single piece of sheet metal, to the ends of which are secured wedge shaped pieces by any suitable means, the lower edge being curved, so that the inner edge will correspond 55 with the diameter of the axle, while the upper edge is flanged outwardly and provided with openings, through which the ends of the securing-bolts pass, as fully shown in Figs. 2 and 3 of the accompanying drawings. Instead 60 of striking this axle bearing or support up out of sheet metal, I may employ a solid wedge-shaped transverse block, as shown in Fig. 5, which can be embraced near each end by a bail, which will pass through the board A and 65 through the attachments on the upper portion of the truck, so as to hold them in position, above which the securing-nuts are located.

C refers to the axle, which is suitably supported in bearings, as hereinbefore described, 75 and said axle may be free to rotate in said bearings. Upon the projecting ends of the axle are mounted wheels D D, said wheels being secured upon the axle by pins d, which pass through perforations therein. Between 80 the bearing for the axle and the wheels are located washers e.

It will be observed that both the axle and wheels are free to revolve, though, if desired, I may construct the parts so that the axle will 85 be stationary and the wheels revolve thereon, or vice versa.

E refers to the points, which are secured to the upper edge of the lower end of the truck by the same bolts which secure the axle-bearing thereto. The base of these points, which are at substantially right angles with the projecting portion, are provided on their under sides with recesses f, which extend from one end thereof to a point where they are provided 90 with transverse recesses f', within which lie the inturned ends of the swinging nose or bail G. Within the recesses f are placed flat springs F, one end of said springs being held in position 95 by the recesses and one of the bolts which 100

passes through the same. Beneath these springs F the upper edge of the board A is cut away, so as to give ample play for the springs.

The swinging nose or bail G is provided with 5 inturned ends, which engage with recesses f', hereinbefore referred to, and these inturned ends have two of their sides formed at right angles to each other, so that the spring which bears upon the same will hold the swinging 10 nose or bail either against the points E or flat upon the truck.

A truck constructed in accordance with my 15 improvements, as shown in the accompanying drawings, may be used for handling boxes, barrels, or bags, and having but one handle it can be advantageously used in moving articles around counters or in a crowded room. In moving barrels or boxes it is only necessary to move the truck against said box, so as to let 20 the points bear against the barrel or box, when it may be tilted upon the truck, the points preventing the barrel or box sliding or rolling off in any direction.

When handling bags or articles which the 25 points would be liable to damage, the swinging nose or bail can be swung in position, so as to project beyond the points, and said bail will be held in whatever position it may be placed by the springs, hereinbefore referred to.

30 The axle-bearing on the under side of the truck not only forms a support for the axle, but also re-enforces and strengthens the bottom portion against splitting, and it will be observed that the same bolts which secure the axle-support in position also hold the points to the upper portion of the truck.

I claim—

1. In a hand-truck, the combination of the body, the wheel-axle secured in bearings beneath the body, the points E, secured to the 40 upper surface of the body by the bolts which secure the bearings, and a swinging bail having inturned ends, which are journaled in recesses formed in the under surfaces of the bases of points E, substantially as described. 45

2. The combination, in a hand-truck, of the points E, provided above the bottom portion, A, with recesses f and f', a spring, F, and bail G, having inturned ends with angular faces, against which the spring contacts, substantially 45 as shown, and for the purpose set forth.

3. The combination, in a hand-truck constructed substantially as described, of a transverse axle-support, bolts for attaching said axle-support to the body portion of the truck, 50 and points E, provided with perforations through which bolts pass, a spring, F, secured under the portions E by one of the aforesaid bolts, and a swinging bail, G, substantially as shown, and for the purpose set forth.

4. The combination, with a hand-truck constructed substantially as described, of a handle, B, consisting of parallel side pieces having inturned portions b' and a hand grasping cross-bar, substantially as shown, and for the purpose set forth. 55

In testimony whereof I affix my signature in presence of two witnesses.

EMORY J. BENEDICT.
